UNITED STATES PATENT OFFICE.

HARRY WEARNE, OF RIXHEIM, GERMANY, ASSIGNOR TO J. ZUBER & CIE.,
OF SAME PLACE.

DESIGN FOR WALL-PAPER.

SPECIFICATION forming part of Design No. 29,694, dated November 15, 1898.

Application filed October 19, 1898. Serial No. 694,037. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, which represents a plan view of a portion of a strip of wall-paper embodying the features of my design.

The design consists in the representation of a chain or string of roses, full and partially blown and in the bud, together with foliage, the flower chain or string being uninterrupted.

I claim—

The design for wall-paper herein shown and described.

HARRY WEARNE.
